[57] CLAIM

The ornamental design for a "movie reel clock", as shown.

DESCRIPTION

FIG. 1 is a right front perspective view of a clock showing my new design;

FIG. 2 is a front elevational view thereof;

FIG. 3 is a top view thereof;

FIG. 4 is a right side elevational view thereof;

FIG. 5 is a bottom view thereof;

FIG. 6 is a left side elevational view thereof; and,

FIG. 7 is a rear view thereof.

The broken line showings of photographs in FIGS. 1 and 2 are for purposes of illustration of environment only and form no part of the claimed design.
